(57) **CLAIM**

The ornamental design for a carrier for extrusion and pelletizing equipment, as shown and described.

DESCRIPTION

FIG. 1 is a perspective view of a carrier for extrusion and palletizing equipment showing my new design;

FIG. 2 is a top view thereof;

FIG. 3 is a bottom view thereof;

FIG. 4 is a front view thereof;

FIG. 5 is a rear view thereof;

FIG. 6 is a left side thereof;

FIG. 7 is a right side view thereof;

FIG. 8 is a perspective view of a second embodiment of a carrier for extrusion and palletizing equipment;

FIG. 9 is a top view thereof;

FIG. 10 is a bottom view thereof;

FIG. 11 is a front view thereof; and

FIG. 12 is a rear view thereof.

FIG. 13 is a left side view of a modified form for a carrier for extrusion and pelletizing equipment; and,

FIG. 14 is a right side view of a modified form for a carrier for extrusion and pelletizing equipment.
